EMISSION INDICATOR

Zigmund W. Wilchinsky, Washington, D. C., assignor, by mesne assignments, to the United States of America as represented by the Secretary of the Navy

Application December 10, 1945, Serial No. 634,106

4 Claims. (Cl. 315—369)

1

This invention relates to a method and means for detecting the presence and relative magnitude of thermionic grid emission in vacuum tubes.

A serious problem frequently encountered in high-power vacuum tube applications is that of thermionic electron emission from grid wires. In high frequency tubes particularly, spacings between elements within the tube are small and peak anode voltages and cathode currents may be very large. As a result, minute particles of electron emitting material are often drawn away from the cathode and deposited on the grid. This process, usually called "grid contamination," eventually results in a condition wherein the grid itself emits electrons in substantial numbers when it reaches the relatively high temperature at which the grid of a power tube normally operates. Substantial thermionic emission from the grid causes erratic tube behavior, which may include blocking, frequency instability, short cathode life and refusal to oscillate. In the interest of dependable operation, it is highly desirable that the presence of grid emission be detected at the earliest possible stage of contamination, in order that a contaminated tube may be replaced before rather than after it causes system failure.

It is accordingly an object of this invention to provide a method and means for detecting the presence and relative magnitude of thermionic grid emission in vacuum tubes.

The operation of the invention rests upon the fact that the grid of a vacuum tube has appreciable mass and therefore does not cool instantly when the vacuum tube is cut off from its power source. Hence it is possible, by suddenly removing the power from the tube, to detect grid emission before the grid cools, by means to be herein-after described.

The method and means of this invention are thus particularly adapted for use with tubes which are in anode-pulsed service, wherein a very large voltage is applied between anode and cathode recurrently for very short periods, separated by much longer periods wherein the anode voltage is zero. This results in operating the tube for short periods at a very high power level, separated by much longer periods of inactivity. The type of operation just described is encountered in echo-ranging and pulse-communication systems, and represents a large fraction of modern high-frequency applications of power vacuum tubes. In such applications the period of each pulse of anode voltage might be a few mi-

2

croseconds, while the inactive interval intervening between successive pulses might be of the order of several hundred microseconds. This last-named interval is much shorter than the time required for a grid to cool appreciably; hence this invention will provide conveniently a continuous check on the presence of thermionic grid emission in such anode-pulsed vacuum tubes.

The invention will be described with reference to the accompanying drawing, which is a schematic diagram showing an embodiment of the invention incorporated in an anode-pulsed vacuum tube circuit which for illustrative purposes only is shown as a Hartley oscillator.

15 The vacuum tube to be checked for grid emission is denoted by reference character 10, and shown with its cathode grounded. Terminal 30, to which the negative side of the anode voltage supply is to be connected, is also grounded. The anode of tube 10 is connected through radio-frequency choke coil 9 to terminal 20, to which positive anode voltage impulses are to be applied. The anode of tube 10 is also connected through blocking condenser 11 to one side of a tank circuit consisting of inductance 4 and condenser 5 in parallel. The other side of the tank circuit is connected through condenser 7 to the positive side of D.-C. source 3. The negative side of D.-C. source 3 is connected to the grid 30 of tube 10. Condenser 7 is shunted by grid leak resistor 6. D.-C. source 3 is shunted by R. F. bypass condenser 8. Inductance 4 is grounded via an intermediate tap. D.-C. meter 1 is connected between the anode of tube 10 and the cathode of diode 2. The anode of diode 2 is connected to the positive side of D.-C. source 3.

The circuit elements about which the invention is mainly concerned and shown in the illustrated embodiment, are D.-C. meter 1, diode 2, 40 and D.-C. source 3. D.-C. meter 1 may be any sensitive direct-current indicating device, with or without calibration in actual units. D.-C. source 3 may be a small battery or any other D.-C. source supplying a few volts.

45 The operation of the invention, as heretofore stated, depends upon the fact that the grid temperature does not drop sharply after the termination of a pulse of anode voltage. Between anode pulses the anode voltage is substantially zero. Therefore, if the grid is emitting electrons at its operating temperature, grid-to-anode space-current conduction will permit a direct current to flow from D.-C. source 3 through diode 2, meter 1, and within tube 10 between the an-

ode and grid. If such a current flows, an indication on meter 1 will result, serving as a warning that tube 10 has a contaminated grid. If the grid is not emitting electrons at its operating temperature, meter 1 then will at all times read zero.

The presence of the aforementioned components of the invention in this circuit arrangement has no adverse effect on the normal operation of the circuit, since the application to tube 10 of voltage from its power supply causes the cathode of diode 2 to become much more positive than its anode. Consequently, diode 2 is effectively an open circuit during the operative intervals of tube 10 and the presence of the invention has no effect except the negligible one of slightly increasing the grid-anode capacitance of tube 10.

In practice, if complete absence of thermionic grid emission is deemed essential, replacement of tube 10 may be effected immediately whenever meter 1 shows any reading during system operation. If a small amount of grid emission is tolerable, the critical or danger point may be determined by noting the reading of meter 1 at which the contaminated grid begins to cause trouble. When this point has been determined a meter reading somewhat below that critical value may be selected as the warning signal for tube replacement.

The invention, once installed in an anode pulsed vacuum tube circuit, gives a constant check on grid contamination and involves no maintenance problems. If a battery is used as D.-C. source 3, its life is substantially equal to shelf life, since no current is drawn from it except when grid contamination is present, and even then the drain is very small.

It will be understood that the embodiment of the invention herein shown and described is exemplary only and that the scope of the invention is to be determined by reference to the appended claims.

What is claimed is:

1. The method of detecting thermionic grid emission in a vacuum tube including at least an anode, a cathode and a grid, comprising suddenly interrupting the operation of the vacuum tube by cutting off its anode-cathode voltage, applying a voltage between grid and anode, and detecting the presence of grid-anode space current before the grid has appreciably cooled from its operating temperature.
2. The method of detecting thermionic grid emission in a recurrently-operative anode-pulsed vacuum tube including at least an anode, a cathode and a grid, comprising applying a voltage between grid and anode during the intervals between pulses and detecting the presence of grid-anode space current during such intervals.
3. In apparatus comprising a vacuum tube having at least a cathode, a grid, and an anode operative during the application of a voltage between anode and cathode, means for suddenly interrupting operation by cutting off the anode-cathode voltage, and means for applying a voltage source and a current detecting means in series between the grid and anode operative to indicate the presence of emission current from the grid during the interval after the anode-cathode voltage has been cut off and before the grid has cooled appreciably.
4. In apparatus comprising a vacuum tube having a cathode, a grid and an anode operative during the application of recurrent voltage impulses between anode and cathode, a voltage source, a unilateral impedance, and current detecting means connected in series between the grid and the anode operative to indicate the presence of emission current from the grid during the intervals between said voltage impulses.
